(57) **CLAIM**

The ornamental design for a tiger doll, as shown and described.

DESCRIPTION

FIG. 1 is a front perspective view of the tiger doll of the present invention;

FIG. 2 is a front view of the invention of FIG. 1;

FIG. 3 is a rear view of the invention of FIG. 1;

FIG. 4 is a side view of the invention of FIG. 1, as seen from the left side of FIG. 2;

FIG. 5 is a side view of the invention of FIG. 1, as seen from the right side of FIG. 2;

FIG. 6 is a top plan view of the invention of FIG. 1; and, FIG. 7 is a bottom plan view of the invention of FIG. 1. The stippling on the ball and on the right paw represent corresponding hook-and-loop fastening. The stippling on the stripes represent contrasting color with substantially all of the body of the tiger doll. The remainder of the stippling shown in the drawings are intended to represent the approximate three-dimensional contours of the design, and are not intended to indicate any particular color, material, texture or finish.
